UNITED STATES PATENT OFFICE.

GEORGE J. ROMULUS, OF LYNN, MASSACHUSETTS, ASSIGNOR OF ONE-HALF TO ALBERT R. MYERS, OF BROOKLYN, NEW YORK.

DESIGN FOR A LAMP.

61,118.

Specification for Design. Patented June 20, 1922.

Application filed May 12, 1921. Serial No. 469,055. Term of patent 14 years.

To all whom it may concern:

Be it known that I, GEORGE J. ROMULUS, a citizen of the United States, and a resident of Lynn, in the county of Essex and State of Massachusetts, have invented a new, original, and ornamental Design for a Lamp, of which the following is a specification, reference being had to the accompanying drawing, forming part thereof.

The figure is a perspective view, illustrating my new design for a lamp.

I claim:

The ornamental design for a lamp, as shown.

GEORGE J. ROMULUS.
